UNITED STATES PATENT OFFICE.

BARNET A. AUGHINBAUGH AND GEORGE MORROW, OF URBANA, OHIO,
ASSIGNORS TO AUGHINBAUGH & BAKER BROS., OF SAME PLACE.

DESIGN FOR A VEHICLE-BODY.

SPECIFICATION forming part of Design No. 16,086, dated May 12, 1885.

Application filed April 6, 1885. Term of patent 7 years

To all whom it may concern:

Be it known that we, BARNET A. AUGHINBAUGH and GEORGE MORROW, of Urbana, Champaign county, Ohio, have jointly invented and produced a new and original Design or Pattern for Vehicles for Carrying Oils, Milk, Bread, &c., of which the following is a specification.

The novelty of our design consists in a body of a vehicle for carrying oil, milk, bread, &c., whose sides are in the same vertical plane throughout their length, and whose bottom lies in three horizontal planes, as illustrated.

The drawing represents a side elevation of our newly-designed wagon-body.

B B' B² represent the body of the wagon.

C is the drop of the body, which, as shown, is substantially of U shape, the lower part of the U extending some distance below the plane in which the axles would lie.

The bottom of the front portion of the body

(marked B) is higher than the bottom of the rear portion, (marked B²), which in turn is higher than the bottom of the drop.

We claim—

The design for the oil, milk, or bread wagon body herein described and shown, the same consisting in a body whose sides are in the same vertical plane throughout their length, and whose bottom lies in three horizontal planes—that is to say, the bottom of the front portion higher than that of the rear portion and the bottom of the latter higher than the bottom of the drop.

In testimony whereof we affix our signatures in presence of two witnesses.

BARNET A. AUGHINBAUGH.
GEORGE MORROW.
